M. WHEELER.

Gas Regulator.

No. 15,028.

Patented June 3, 1856.

UNITED STATES PATENT OFFICE.

MARSHAL WHEELER, OF HONESDALE, PENNSYLVANIA.

GAS-REGULATOR.

Specification of Letters Patent No. 15,028, dated June 3, 1856.

To all whom it may concern:

Be it known that I, MARSHAL WHEELER, of Honesdale, in the county of Wayne and State of Pennsylvania, have invented a new and Improved Gas-Regulator; and I do hereby declare that the following is a full and exact description thereof, reference being had to the accompanying drawings, making a part of this specification, Figure 10 1 being a vertical section in the line *y y* of Fig. 2; Fig. 2, a horizontal section in the line *x x* of Fig. 1; and Figs. 3, 4 and 5, represent portions of said gas regulator in detail.

15 Similar letters indicate like parts in all the drawings.

The semicircular compartment A, united to the circular compartment D, by the passage *k*, forms the fluid receptacle of my improved gas regulator. The gasometer E, of said regulator, is suspended within the compartment A, by means of supporting journals *g*, *g*, which project from the angles of said gasometer into holes *n*, in the supporting hooks *l*, *l*, that are located near the outer angles of said compartment A, and are suspended from the upper edge of its sides. A rectangular goose neck *d*, which is made fast to the under side of the top of the gasometer, descends and passes through the passage *k*, into the compartment D, where it curves upward nearly to the top of the closing cover F, of said compartment, and then curves forward and downward into a vertical position. The outer extremity of the goose-neck *d*, is brought to an acute angle at its inner side and has a triangular opening *m*, in it, as represented in Figs. 1 and 5. At the inner end of said goose-neck, two lateral openings *h*, *h*, communicate with the interior of the gasometer.

Underneath the compartment D, is a chamber C, which is connected to the street main by suitable connections, and which 45 communicates with the said compartment D, by means of the vertical pipes *c*. The said chamber C, is divided by the partition *r*, from the chamber B, which is situated immediately below the compartment A, of the 50 fluid receptacle.

The interior of the gasometer E, above the surface of the fluid, communicates with the chamber B, through the medium of the vertical tube *f*, and the said chamber B, is connected with the gas distributing pipes in a 55 building.

The fluid in the gas regulator, should rise nearly to the upper ends of the tubes *c*, *c*, and *f*,—and must not be permitted to fall so low as to permit the gas to escape through 60 the slot in the side of the cover F, that the goose-neck works in. The gas entering the chamber C, through the tube *a*, from the street main, rises through the tubes *c*, *c*, into the close top of the cover F, of the compartment D, and entering the goose-neck *d*, flows into the gasometer E, and thence through the tube *f*, into the chamber B, from whence it is conducted through the distributing pipes to the burners. A bent lever *i*, rises from the inner side of the gasometer, and the notched horizontal portion of 65 said lever extends outward over the top of the gasometer. By suspending a poise *j*, in different positions upon the said arm *i*, 70 the amount of gas suffered to pass through the regulator, can be accurately governed, and the pressure thereof upon each square inch of the surface of the gasometer, the chamber B, and the distributing pipes, be 75 accurately ascertained.

The buoyancy of the gas within the gasometer will of course cause it to rise, and this movement of the gasometer, will dip the outer end of the goose-neck *d*, into the fluid 85 in the regulator, and thereby diminish the size of its aperture, *m*, through which the gas flows to the gasometer. Therefore, if there is a very great pressure of gas in the street main, the gasometer of the regulator 90 will rise, and thereby diminish the exposed portion of the aperture *m*, in the end of the goose-neck at which the gas enters; and if there is a less degree of pressure in the street main, the gasometer of the regulator 95 will fall, and thereby enlarge the exposed portion of the aperture *m* for the gas to enter the goose-neck and flow on to the gasometer. It will therefore be perceived 100 that the quantity of gas that can enter and pass through the gasometer will depend entirely upon the weight of the gasometer. If the said gasometer is heavily weighted, there will be a corresponding pressure of 105 gas within it, and vice versa. The force of the gas within the street main, will exert no effect upon the gas regulator, unless it should fall below that at which the regulator is gauged for; and in that case, the gasometer will sink and allow the gas to 110 flow at its reduced force through the regulator to the burners.

Having thus fully described my improved gas-regulator, what I claim therein as new and desire to secure by Letters Patent, is—

The combination of the gasometer and its 5 goose-neck, with the fluid receptacle and with the graduated lever *i*, and the weighing poise *j*, substantially as herein set forth.

The above specification of my improvement in gas regulators, signed this seventh day of March, 1856.

MARSHAL WHEELER.

Witnesses:

EARL WHEELER,
O. D. GUSTIN.
